CONTINUOUS SHEET FACSIMILE SYSTEM

William G. H. Finch, Spuyten Duyvil, N. Y.

Application February 3, 1937, Serial No. 123,770

11 Claims.

(Cl. 178—11)

This invention relates to facsimile systems and more particularly relates to mobile transmitters employing pictures or messages to be transmitted from a continuously fed sheet.

- 5 The objects of my present invention reside in providing a rugged, compact, mobile facsimile transmitting unit of a fool-proof and light weight design; to provide improved scanning mechanism; to provide simplified and positive sheet feeding and adjusting apparatus; and to provide simplified optical scanning employing a novel cam and cam follower arrangement.
- 10 The electrical transmission and reception, and synchronizing circuits and arrangements which render my present mechanism particularly practical for mobile facsimile operation is disclosed in my Reissue Patent No. 19,575 of May 21, 1935, entitled "Image broadcasting system." My present invention contemplates structural and mechanical improvements in the scanning and sheet feeding portions of the facsimile units for either transmission or reception and also contemplates simplified structural design.

Following is a description of a preferred embodiment for a mobile facsimile transmitter employing the improvements of my present invention. It is to be understood, however, that these improvements are not confined to a transmitter unit but may be equally well employed for a mobile receiver unit. The mobile receivers are particularly useful for home broadcasting or aircraft, ship and automobile use and where a compact and relatively inexpensive system is required.

Figure 1 is an elevation of a mobile transmitter with the cover removed.

Figure 2 is a plan view of the transmitter unit.

Figure 3 is an enlarged cross-sectional view taken along 3—3 of Figure 2 illustrating details of the scanner and sheet feeding mechanism.

40 Figure 4 is a cross-sectional view taken along 4—4 of Figure 3 through the light source.

Figure 5 is a partial plan view corresponding to the section taken along 5—5 of Figure 1.

45 Figure 6 is a front view of the flexible spring for clamping the record sheet in scanning position.

Figure 7 is a portion of Figure 5 illustrating the flexible sheet holding spring in open position.

50 Figures 8 and 9 are detail views of the sheet feeding mechanism.

Referring to the figures and more particularly to Figures 1 and 2, there is shown a cast iron base 10 for supporting the mechanism in horizontal position. A drive motor 11 is mounted on base 10 and is rotated in a continuous manner

during the operation of the transmitter unit. I prefer to employ a synchronous motor for connection to a standard alternating current source such as sixty cycles and operative at, for example, 1800 revolutions per minute. It is to be understood that a similar motor is employed at the associated receiving units. The shaft of motor 11 is geared down to the scanning speed by suitable means such as a worm and pinion enclosed in the casing 12. A suitable scanning speed for 10 mobile facsimile work is sixty lines per minute corresponding to sixty revolutions per minute of the vertical driven shaft 13 positively connected to the motor 11 at the reduction gearing within casing 12. The bottom of driven shaft 13 is 15 connected to gear 14 which drives the cam 15 through a gear 16 meshing therewith and attached to cam 15. Cam 15 oscillates the optical scanning mechanism 17 horizontally across the record sheet 18. A cam follower 19 coacts with 20 the cam 15 to operate the scanning mechanism in a manner to be described in more detail hereinafter. A cam 20 is attached to the top of the driven shaft 13 to actuate the sheet feeding mechanism 21 for advancing the record sheet 18 25 line by line past the oscillating scanner 17.

The record sheet 18 may be inserted in the transmitter unit as a continuous roll 22 whereby long reports, messages, series of pictures or the like may be broadcast to a plurality of receivers. 30 In my preferred transmitter, I employ an optical scanning system for scanning an opaque record sheet so that the actual messages and pictures may be directly transmitted. However, modifications such as described in my reissue patent 35 referred to above may be made for transmission of translucent records.

The electrical circuits and components for translating the electrooptical impulses and providing the synchronizing signals are not illustrated in order to simplify the disclosure of the present invention. However, it is to be understood that most of the electrical equipment may be housed within the illustrated unit and upon the base 10 thereof. The cover for housing the 45 whole transmitter is also not illustrated but is used in a commercial unit to improve the over all appearance, prevent dust accumulation and exclude extraneous light from the optical system.

Figure 3 is a vertical cross-section taken along 50 the axis 3—3 of Figure 2 to illustrate the preferred electrooptical system 17 in more detail. The whole optical system 17 is oscillated across the sheet and supported by vertical rod 23 set into the bracket 24 and base 25. The cam follower 55

- 19 is attached to rod 23 by a suitable bracket 26. Rod 23 is rotatably mounted in its supporting structure to permit the oscillation of the optical system 17.
- 5 The source of light for the optical system comprises an electric bulb 27 with its filament supported opposite a telescoping condensing lens system 28 focussed upon the record sheet 18. The diameter of the spot of light focussed upon sheet 18 is substantially equal to the width of the scanning line. Accordingly, where sixty line per inch of scanning is employed, a spot about $\frac{1}{60}$ " in diameter is used. The record sheet 18 will accordingly progress one inch per minute through 10 the transmitter when sixty lines per inch and sixty revolutions per minute are used. It is to be understood that different speeds and rates 15 may be incorporated in practical designs.
- A photoelectric cell is enclosed in the tubular 20 housing 30 supported by a plate 31 attached to the lamp enclosure 32. A lens system 33 projects from the tubular housing 30 for focusing a portion of the refracted light rays 34 from the sheet 18 to the photoelectric cell not shown. The 25 electrooptical technique of generating a light beam and focusing upon a photoelectric cell to transform the varying light intensities of the transmitted picture 18 into corresponding varying electrical currents to be transmitted, is well 30 known in the facsimile art. However, the novel and compact arrangement of the scanning mechanism 17 upon the oscillating shaft 23 simplifies the construction. The photoelectric cell is oscillated across the continuous sheet 18 together 35 with the lens system 28 to continuously scan the record sheet 18 line by line. The picture sheet 18 is advanced one line corresponding to each oscillation of the electrooptical scanner 17 as 40 will be described hereinafter.
- 40 The light source 27 may be focused into a sharp beam 35 by suitably positioning its filament with respect to the condensing lens system 28. Figure 4 is a cross-sectional view taken along 4-4 of 45 Figure 3 to illustrate the eccentric mounting of the lamp 27 for adjusting the position in a simple manner. The lamp 27 is mounted in a circular supporting base 39 and in a tube 37 projecting from base 39 positioned off center with respect 50 to the base 39. The base 39 is rotatably supported in the lamp housing 32. By manual rotation of the tube 37 and base 39, the off center position of the tube 37 will correspondingly cause the lamp 27 to move closer to or further away 55 from the optical system 28. Adjustment as much as $\frac{1}{16}$ " may readily be performed by this arrangement. The condensing lens system 28 may further be telescoped in the well known manner to aid in proper focussing of the sharp beam 35.
- 60 The optical system 17 may be raised sufficient to cause the axis of the condensing lens system 28 to be raised above the opaque block 36 so that the beam 35 may project beyond the transmitter unit, the record sheet 18 not being in position at 65 this time so that a sharp focusing of the beam is facilitated. A hollow tube 38 projects from the lamp enclosure 32. A cap 40 is attached to the top of hollow tube 38 in spaced relation to permit circulation of air to the lamp 27 for ventilation and cooling.

Figure 5 is a partial plan view corresponding to the section taken along 5-5 of Figure 1 illustrating in more detail the scanning actuation of the electrooptical system by the cam 15 continuously rotated by the motor. The cam follower

19 is mechanically biased against the cam 15 by means of a spring 41 connected between the follower bracket 26 and a frame portion 42. The surface of the cam moves the follower 19 to the extreme positions 19' and 19" shown in dotted. 5 The outer position 19' corresponds to the point 43 at the maximum radius of the cam 15; the inner position 19", to the point 44 at the minimum radius. The dot dash circle 45 corresponds to the locus of the movement of point 43; 10 the smaller circle 46, to the movement of the inner point 44. For each rotation of cam 15 the optical system 17 is oscillated back and forth once horizontally across the sheet 18. The optical scanning of the picture shading occurs during 15 one traverse of the sheet 18; and the synchronizing signal and sheet advancing actuation occurs during the return or opposite motion of the scanning mechanism 17.

In order to insure quality scanning, the record 20 sheet 18 must be held firmly in position opposite the oscillating scanner. However, for ease of insertion and removal of the sheet 18 from the unit, means are provided for disengaging the sheet from its rigidly held position. The im- 25 portant feature of my present invention resides in the improved sheet engaging and disengaging mechanism to perform this operation with a minimum of effort from the operator. Figure 6 shows a leaf spring 47 pressing against the block 36 with the record sheet 18 held in position there- 30 between. A slot 48 provided across the central portion of the spring 47 corresponds to the section of the sheet 18 to be scanned. The relation between the scanning beams 34 and 35, the leaf spring 47, the record sheet 18, and the opaque block 36 is clearly illustrated in Figure 3. The flat spring 47 presses the sheet 18 firmly against the opaque block 36 to hold it in scanning relationship. However, sheet 18 may be 40 moved from engagement with the spring 47 and block 36, the sheet feeding force overcoming the frictional engagement of the sheet 18 at this point. I prefer to use an opaque block 36 for supporting the sheet 18 at the portion being 45 scanned in order to permit better contrast during the scanning operation.

One end 50 of the flexible or spring plate 47 is pivotally supported at a bracket 51 attached to the block 36. The opposite end 52 of the sheet 55 spring 47 is attached to one end of lever 53 which permits manual engagement or disengagement of the spring 47 against the record sheet 18. The end 52 of spring 47 presses against the curved end 54 of lever 53. Spring 47 normally tends to assume the open position illustrated in Figure 7 whereby the sheet 18 is not held in firm engagement opposite the lens system 28. The pivoted lever 53 is mechanically biased by spring 55 to force the end 52 of leaf spring 47 inwardly forcing the flexed spring 47 to press the sheet 18 against the block 36 and hold it in proper engagement. To maintain the spring 47 in the unengaged position shown in Figure 7, a latch 56 is clearly illustrated in Figures 7 and 8. When 65 the latch 56 is released from lever 53 the spring 47 is snapped against the record sheet 18 due to the biasing action of spring 55.

Further means for holding the record sheet 18 in proper alignment is provided near the top of 70 the machine by coacting rollers 57 and 58. These are preferably rubber rollers for frictionally engaging the sheet 18. The larger roller 57 is connected to a shaft 60. A hand lever 64 is attached to one end of a shaft 60 for manually advancing 75

the record sheet 18 through the facsimile unit. The line by line advancing mechanism 21 is attached to the opposite end of the shaft 60 for automatically advancing the sheet 18 during the scanning operation in a manner to be described. Smaller roller 58 is an idler or presser roller for maintaining the sheet 18 in frictional engagement with the roller 57. The roller 58 may be formed in two sections as illustrated in its plan view in Figure 2.

The presser roller 58 is arranged to be snapped into position against the sheet 18 and roller 57 or, conversely, snapped out of engaging position. The dotted position 58' shown in Figure 3 illustrates the out of engagement position of presser roller 58. The opposite supporting arms 63 for the roller 58 are connected to corresponding springs 62 attached between the arm and the uprights 64. Springs 62 maintain the presser rollers 58 in engaged or disengaged position by the off center action as illustrated.

Figure 8 is an enlarged end view of the pawl and ratchet line by line advancing mechanism 21. The rocker arm 65 is moved back and forth by the cam 20 shown in Figure 1. A follower 66 coacts with the cam to rock lever 67 and correspondingly move rod 65 to and fro. The end 68 of rod 65 is pivoted to a feed pawl 70. The pawl 70 engages the teeth of ratchet wheel 71. Ratchet wheel 71 is attached to the shaft 60 of feed roller 57 (Figure 3). Feed pawl 70 is pivoted on arm 72 and spring biased into engagement with the teeth of ratchet wheel 71. A further pawl 73 is spring biased against the ratchet wheel 71 to prevent reverse rotation of the ratchet wheel and the sheet feeding mechanism. For each rotation of the cam 20, rod 65 will be rocked once to advance the ratchet wheel 71 by one tooth. The record sheet 18 will be advanced by a distance equal to one scanning line in response to this operation as will now be understood.

Figure 9 is an enlarged detail view corresponding to 9-9 of Figure 2 illustrating the coaction between the ratchet wheel 71 and the feed roller 57. A pinion 74 is secured coaxially with ratchet wheel 71 across the upright 64 and engages with a gear 75 attached to the shaft 60 of roller 57. The gearing ratios and diameters of the components of the feeding mechanism are arranged so that the advancement of one tooth of ratchet wheel 71 will move the record sheet by a distance equal to the width of one scanning line.

Although I have described a preferred embodiment for my present invention, modifications may be made by those skilled in the art which fall within the broader spirit and scope of my present invention and accordingly I do not intend to be limited except as set forth in the following claims:

I claim:

1. Mechanism for maintaining a sheet in arcuate alignment for line-by-line scanning comprising a flat flexible plate; an arcuate member substantially coextensive with said plate, the sheet being placeable between said plate and said member; and means for pressing said plate against said sheet to cause said sheet to continuously conform with said arcuate member transversely across the sheet and to frictionally engage said sheet between said plate and member.

2. Mechanism for maintaining a sheet in arcuate alignment for line-by-line scanning comprising a flat flexible plate; an arcuate member

substantially coextensive with said plate, the sheet being placeable between said plate and said member; means for normally pressing said plate against said sheet to cause said sheet to continuously conform with said arcuate member transversely across the sheet and to frictionally engage said sheet between said plate and member; and manually operable means coactable with said pressing means for holding said plate in open position.

3. Mechanism for maintaining a sheet in arcuate alignment for line-by-line scanning comprising a flat spring having a transverse slot; an arcuate member substantially coextensive with said spring; said transverse slot being positioned opposite the line of scanning and the sheet being placeable between said flat spring and said member; and means for pressing said flat spring against said sheet to cause said sheet to continuously conform with said arcuate member transversely across the sheet and to frictionally engage said sheet therebetween.

4. Mechanism for maintaining a sheet in arcuate alignment for line-by-line scanning comprising a flexible plate; an arcuate member, one end of said plate being pivotally attached to said member, the sheet being placeable between said plate and said member; and means for pressing said flexible plate against said sheet to cause said sheet to continuously conform with said arcuate member transversely across the sheet and to frictionally engage said sheet between said plate and member.

5. Mechanism for maintaining a sheet in arcuate alignment for line-by-line scanning comprising a flat spring having a transverse opening; a member, one end of said sheet spring being attached to said member; said transverse opening being positioned opposite the line of scanning and the sheet being placeable between said flat spring and said member; and means for pressing said flat spring against said sheet to cause said sheet to continuously conform with said member transversely across the sheet and to frictionally engage said sheet therebetween comprising a lever coacting with the other end of said flat spring for flexing said spring against the member.

6. Mechanism for maintaining a sheet in arcuate alignment for line-by-line scanning comprising a flexible plate having a transverse slot; an arcuate member of opaque material, one end of said plate being pivotally attached to said member; said slot being positioned opposite the line of scanning, the sheet being placeable between said plate and said member; and means for pressing said plate against said sheet to cause said sheet to continuously conform with said arcuate member transversely across the sheet and to frictionally engage said sheet therebetween comprising a spring biased lever coacting with the other end of said plate for flexing said plate against the member, whereby the line-by-line scanning of the gripped sheet occurs across said slot.

7. Mechanism for maintaining a sheet in arcuate alignment for line-by-line scanning comprising a flat flexible plate having a transverse slot; an arcuate member of opaque material, one end of said plate being pivotally attached to said member, said transverse slot being positioned opposite said scanner, the sheet being placeable between said plate and said member; means for pressing said plate against said sheet to cause said sheet to continuously conform with said

arcuate member transversely across the sheet and to frictionally engage said sheet therebetween comprising a spring biased lever coacting with the other end of said plate for flexing said plate against the member, whereby the scanning of the gripped sheet occurs across said slot; and manually operable means coactable with said pressing means for holding said plate in open position consisting of a latch for engaging with said lever.

8. In facsimile scanning apparatus, an arcuate platen, a sheet thereon, spring pressed clamps for holding said sheet upon the convex surface of said platen at a plurality of points thereon, means

15 common to all said clamps to raise same to release said sheet, a member movable over the sheet, and translating means carried by said member and adapted to contact said sheet.

9. In facsimile scanning apparatus, an arcuate 20 platen, a sheet thereon, spring pressed means for holding said sheet upon the convex surface of said platen at a plurality of points thereon, means common to all said clamps to raise same to release said sheet, means for moving said sheet

across said platen step-by-step, a member movable over the sheet, and translating means carried by said member and adapted to cooperate with said sheet when same is stationary on said platen.

10. In facsimile scanning apparatus, a convex stationary platen, a sheet supported on the convex face of said platen, means comprising resiliently mounted arcuate clamps engaging said sheet and extending transversely across the same 10 adjacent to the ends of said platen, and means common to said clamps for disengaging them from said paper.

11. In facsimile scanning apparatus, a convex stationary platen, a sheet supported on the convex face of said platen, a pair of arcuate clamping members extending transversely across said sheet for holding the latter in intimate contact with said platen, a translating device and means for moving the same in a path between said 15 clamping members, and means common to said clamping members for raising them to a position spaced apart from said platen.

WILLIAM G. H. FINCH.
